HEATING SYSTEM

Carl R. Meek, Detroit, Mich.

Application January 9, 1932, Serial No. 585,711

1 Claim. (Cl. 237—2)

This invention relates to heating systems. One of the objects of the invention lies in the provision of a zone system of heating for a dwelling, in which one single heating unit is used in a manner to provide a steam heating system for one portion of the dwelling and a hot air system for another portion thereof.

Another object lies in the provision of a heating system in which a heating unit such as a steam boiler is used, the same being fired by an automatically controlled device such as an oil or gas burner, the boiler being connected in an operative manner with a forced draft hot air unit in such manner as to provide a steam heating system for one zone of a dwelling and a hot air system for the remaining portion of the dwelling.

Still another object lies in providing a heating system which includes an automatically fired steam boiler and a hot air unit including a radiator portion having a circulating hot water connection with the boiler, there being provided a fan member in the hot air system for propelling air over the hot air radiator and an automatically operating control system which insures automatic heating of a dwelling in two zones, one zone being heated by steam and the other by hot air.

A further object lies in the provision of a single heating system including a steam boiler and a co-operating forced hot air system, the system being controlled by dual thermostats in two zones of the dwelling to be heated, the thermostats insuring automatic and satisfactory heating of either zone of the dwelling without affecting the other zone.

Other objects will appear in the following specification, taken in connection with the annexed drawings, in which

Fig. 1 is a combined elevation and diagrammatic showing of my dual zone heating system; Fig. 2 is an elevational view, partially in section, showing the hot air portion of the heating unit; and

Fig. 3 is an end elevation of Fig. 2.

Generally it might be stated, that the present system is a single fired heating system, which is adapted to furnish two zones of a dwelling with different types of heat. In other words, a hot air system of heating has been found to be the most practical for several of the rooms of the ordinary home, such rooms being the hall, dining room, living room, library, etc. However, this system of heating, which lends itself readily to automatic humidification and air conditioning, is not as practicable when the upper or bed rooms

of the home are concerned, in view of the fact that the windows are ordinarily left partially open during the night and operate in this way to provide pure air at a time when most needed. Steam heating lends itself more particularly to the instantaneous heating of a bed room and especially has the advantage of permitting radiators to be partially closed when a minimum of heat is desired.

From applicant's experience in the installation of various heating systems, he has found that a combined steam and hot air system of the zone type is highly desirable. It is necessary, however, that the two zones of the house be controlled separately.

The ordinary home having an automatically fired heating system is usually controlled by a single thermostat, which of course cannot insure efficient heating of all the rooms of the dwelling. The art will show various separate thermostatic controls for various portions of a dwelling; however, applicant is not interested in this character of device, but desires a zone heating device with separate automatic control.

Referring to the drawings, applicant's system is presented in a somewhat general manner; for instance, a low pressure type of steam boiler is shown at 10. The details of a boiler of this type are so well known as to make detail description unnecessary.

Means for firing the boiler in an automatic manner is provided by any well known type of burner, which is referred to generally as 11. Obviously, any type of automatically controlled burner may be used.

The dwelling to be heated is shown generally as made up of two zones A and B, the former referring to the lower portion of the dwelling adapted to be heated by hot air, and B, the upper or bed rooms of a dwelling which are perhaps better heated by steam. The connection between the steam boiler and zone B is designated as 12, which comprises a conventional steam pipe connected with a radiator 12'. Obviously, this type of system is sufficiently well known to obviate a detail disclosure of radiators, etc. Similarly, with respect to zone A, it has not been thought necessary to show other than the ordinary hot air pipe 13 entering this zone.

With respect to the heating of zone B, the automatically controlled heating device creates pressure within the steam boiler 10. The water in the boiler is normally held at a minimum temperature slightly below boiling by means of the aquastat 14 which operates to maintain the water

at the subboiling temperature by controlling the burner. This control of the burner is through the electric connection 15, which in turn controls the burner through the conventional relay 16, 5 which in turn controls the burner through the electrical connection 17 in the well known manner. In other words, the aquastat is a water temperature control for the operation of the burner, although the actual control of the steam 10 heating system is from the house thermostat 18 located in the zone to be heated by steam heat.

The effect of the operation of a system of this character is substantially the same as if two heating systems of different type were used, although 15 in the present instance, it is quite obvious that there is but one heating system, while the hot air system forms a part of and operates in conjunction with the steam heating system.

With special reference to the hot air system, 20 a casing for the air heating system has been designated 19. The interior of this casing is divided by means of a partition to form therein two compartments, one of which forms a duct through which return air may pass, if desired, 25 through a conditioning filter 21 from an inlet 20 to an aperture 22. The incoming air passes directly through aperture 22 into a fan of conventional construction 23. This fan is rotated by an electric motor of conventional construction 24, 30 the drive being of a chain or belt type 25, the chain passing about a pulley 26 which rotates the blade portions of the fan. The chain 25 also passes over a second pulley 26, secured to the shaft of a conventional water pump 27 whereby 35 water from boiler 10 is forcibly circulated through radiator 28.

The incoming air is exhausted by pressure 40 through the hot water radiator 28, which may be of any desired construction, although in the present instance the same is shown to be of a fin type. The air, in passing over the radiator, obviously is heated and is forced directly into the hot air pipe 13, which communicates with suitable outlets in zone A of the dwelling.

45 For simplicity, as stated above, the zones have been shown merely in a diagrammatic manner.

Now, as respects the manner of circulating the water from the steam boiler to the radiator 28, in the first instance the radiator is disposed lower 50 than the heated water in the boiler 10. A pipe connection between the radiator and boiler is shown at 29. Means for circulating the water is accomplished through the before mentioned water pump 27, which is connected to the radiator 55 by means of the pipe 31. An electric connection 32 is shown between the electric motor 24 and a relay 33 controlled by the house thermostat 34 located in the hot air zone A.

60 The operation of the system is controlled by means of two thermostats 18 and 34 which operate independently of each other. One thermostat, located in the steam heated zone and designated 18, controls the operation of the burner by direct connection through a relay 16 with the 65 motor of the burner. This is in the manner customary in steam installations today. The second thermostat 34, located in the warm air heated zone, will control the operation of the burner and delivery of heat as follows: The

thermostat makes direct connection through the relay 33 with the motor of the air heating unit, which in turn drives the fan and the water pump 27. As the fan and water pump are brought into operation, the temperature of the water in the steam boiler is lowered and the burner then brought into operation by the functioning of the aquastat 14. The control in the case of either zone is entirely automatic.

80 The results of a system of this character will be a combined steam and air heating system, using a single heat source in which the steam and warm air units operate entirely independently of each other. They will either simultaneously or at different times perform their full function. The temperature of the steam zone may be brought up to the desired degree without in any way affecting that of the other zone, and likewise, that of the warm air zone may be controlled independently of the steam zone. 85 Further, the storage of heat in the water of the boiler makes heat instantly available for the warm air zone by merely bringing the air unit into operation.

90 It might be further noted that the complete 100 independence in the operation of the two units and control of temperature in the two zones is effected without the use of valves, either pressure or thermostatically controlled. Applicant employs the characteristic properties of water 105 and steam as affected by changes in temperature through the addition of heat. Water up to boiling point is used as an element of heat transmission for the air heating unit and when heat is desired in the steam heated zone it is accomplished by the addition of more heat and the generation of steam.

95 What I claim is:

110 A system for heating dual zones, including means for independently and automatically heating 115 said zones from a single heating unit, including a steam boiler, automatically operated means for heating said boiler, a steam heating connection between the boiler and one of the zones to be heated, an air heating unit including a warm air conduit connected to a second zone to be heated, a radiator in said heating unit connected with the steam boiler, means for forcing returned air over the radiator in such manner that warm air is forced to the last named 120 zone, automatically operating means for independently controlling the heating of the two zones including a thermostat in the steam heated zone controlling the operation of the heating means for the steam boiler, a second thermostat 125 in the warm air heated zone controlling the operation of the warm air system, and a temperature control in the steam boiler operating to control the operation of the burner in such a manner that water in the boiler is automatically 130 maintained at a temperature below boiling when the thermostat of the steam heated zone is not calling for heat whereby heat may be supplied to the air heated zone without generation of steam for the steam heated zone to insure a supply of hot water for the radiator in the air heating unit.
